UNITED STATES PATENT OFFICE.

EBENEZER A. W. JEFFERIES, OF WORCESTER, MASSACHUSETTS, ASSIGNOR TO
MORGAN CONSTRUCTION COMPANY, OF WORCESTER, MASSACHUSETTS, A
CORPORATION OF MASSACHUSETTS.

GAS-PRODUCER.

1,284,694.

Specification of Letters Patent.

Patented Nov. 12, 1918.

Application filed January 23, 1915. Serial No. 4,050.

To all whom it may concern:

Be it known that I, EBENEZER A. W. JEFFERIES, a citizen of the United States, residing at Worcester, in the county of Worcester 5 and Commonwealth of Massachusetts, have invented a new and useful Improvement in Gas-Producers, of which the following, together with the accompanying drawings, is a specification.

10 The present invention relates to gas producers, and has particular reference to the provision of means for automatically controlling and regulating the supply of fuel to the combustion chamber of a device of 15 this class.

Gas producer practice has evolved the mechanical feeding of fuel to the producer chamber, and various mechanisms have been devised to supply such fuel continuously at a 20 rate in accordance with the normal rate of consumption of fuel by the producer. In order to correct the tendency of the fuel thus supplied to pile up at certain portions of the surface of the fuel bed, it has been 25 proposed to locate the feeding device eccentrically with respect to the fuel bed, and to cause relative bodily rotation between said bed and said device, thereby effecting a more or less equal distribution of the incoming 30 fuel upon the surface of said bed.

Difficulties, however, have been made manifest in the operation of such mechanical feeding devices for continuously supplying fuel in predetermined quantities to the fire, 35 by reason of variable conditions imposing themselves upon the operation of the producer, whereby the rates of fuel consumption or ash discharge, or both, are, to a considerable degree, variable; as a result, the mean- 40 level of the fuel bed is not maintained constant, or even substantially so, as said fuel is automatically fed thereto. Instead, the level rises, oftentimes beyond the limit defining a thickness of fuel bed most favorable to 45 the efficient operation of the producer, and under these conditions, it will be seen that the continued constant mechanical feeding of fuel will cause the producer to choke up and be operative only at a serious loss in 50 efficiency.

The present invention is concerned with a means for interrupting or discontinuing the action of the mechanical feeding device when the conditions above described prevail, and

in its essence it consists in providing an agency at all times directly responsive to changes in the level of the fuel bed, for rendering the feeding device inoperative upon the attainment of a predetermined thickness of fuel bed in the combustion chamber of 60 the producer.

The mechanism by which the above and other results are secured is fully set forth in the following description and illustrated in the accompanying drawings, in which— 65

Figure 1 is a vertical sectional view of the upper portion of a gas producer, having my invention applied thereto.

Fig. 2 is a similar view showing the parts in different positions. 70

Similar reference characters refer to similar parts in both figures.

In the form of the invention shown, the gas producer includes a stationary upper or cover section 1, and a rotatable fuel supporting section 2, there being a water sealed joint 3 between said sections to prevent the escape of gases from the combustion chamber 4 inclosed thereby. The section 2, may be rotatably supported in any suitable manner, to receive rotation from the worm 5 which meshes with an annular rack 6 encircling said section. 75

The stationary cover section 1 is utilized, as in ordinary practice, for the introduction 80 of fuel to the producer, being provided with an opening, not shown, through which the fuel enters. In the present instance I have shown a form of mechanical feeding device, designated as a whole by the numeral 7, carried by the section 1 and in operative relation to such opening; said device may partake of the features of any known device of 85 this class, an example of which is found in the mechanism fully set forth and described in the Letters Patent No. 1,221,055, issued to George H. Isley, April 3, 1917. For the 90 purposes of the present invention it is sufficient to state that such feeding device 7 is operable by the rotation of a shaft 8, which drives the interior mechanism adapted to feed fuel at a predetermined rate, to the chamber 4. Said shaft is driven by a ratchet wheel 9, and a pawl or pawls 10, the ratchet wheel being secured to the shaft, and the 95 pawls being pivoted upon an arm or lever 11 arranged to swing upon said shaft. The opposite end of said lever 11 has a horizontal 100

projection or pin 12, received within a substantially semicircular notch or recess 13 in the under side of a link 14, and thereby providing a detachable pivotal connection 5 between said link and said lever. The other end of said link is pivotally connected to one arm 15 of a bell crank lever, pivoted at 16, the other arm 17 of said bell crank being connected to a constantly reciprocating rod or member 18, having a connection with a suitable source of power, not shown.

My invention, as previously stated, contemplates the provision of an agency to 15 which is communicated the variations in the height of the fuel bed during the continuous operation of the producer and, in the present instance, I have shown such agency in the form of a fuel leveling device of the 20 character set forth and described in the Letters Patent issued to Charles W. Lummis and George H. Isley, December 25, 1917, No. 1,251,064. A member 19, carried upon a shaft 20 journaled for swinging movement in 25 bearings 21 supported by the stationary section 1, extends in an oblique position through a large opening in said section 1, with its free end bent at right angles and resting by gravity upon the surface of the 30 fuel in the section 2, as shown in the drawings, preferably in substantially radial disposition thereon. The shaft 20 carries an upwardly extending arm 22 having an adjustable weight 23 thereon serving to vary 35 the pressure of the fuel leveling member 19 upon the surface of the fuel bed, as the latter is continuously rotated beneath said member. A link 24 pivotally connected to the arm 22 has an elongated slot 25 near its 40 other end, which receives a pin 26 carried by an arm 27 projecting upwardly from a shaft 28 journaled in bearings 29 carried by the section 1. The arm 27 carries a weight 45 30; said arm also has an offset substantially right-angled extension 31, disposed beneath the link 14 of the mechanically operated fuel feeding device previously described.

In the normal operation of the producer, with the parts in the positions shown in Fig. 50 1, the constant reciprocation of the member 18 is transmitted to rotate the shaft 8 intermittently by the interposed mechanism, thus securing a mechanical feeding of fuel by the device 7. When such operation takes place 55 under conditions which maintain the level of the fuel bed at substantially the proper height for the most efficient performance of the producer, the arm 22, by reason of the position assumed by the member 19, supports the arm 27, through the connecting link 24, in a position closely approaching the vertical, as shown in Fig. 1. Coincident with a rise in the mean level of the fuel bed, the 60 arm 22 swings to the left, by reason of the angular movement of the member 19 in re-

sponse to the lifting of its free end which rests on said bed. The left hand rocking movement of arm 22 imparts a corresponding rocking movement to the arm 27 and shaft 28; and as soon as said arm 27 is thus 70 carried past the plane of its vertical position by an increase in the thickness of the fuel bed beyond a predetermined limit, gravity will effect the falling of said arm 27 into the position shown in Fig. 2, such movement being permitted by reason of the lost motion pin and slot connection between said arm and the link 24. The above described gravitational movement of the arm 27 carries the short right-angled offset extension 80 31 thereof into engagement with the link 14, lifting said link into the position shown in Fig. 2, with the slot 13 free of the pin 12, so that the reciprocation of said link 14 proceeds with no effect upon the shaft 8 of the 85 mechanical feeding device. As a result, the introduction of fresh fuel to the producer is interrupted, thus preventing the possibility of an excessive height of fuel in the chamber 4. This interruption continues until the 90 operator restores the arm 27 to its normal position; it will be clear that any attempt to restore such arm to normal position, as shown in Fig. 1, before normal working conditions of fuel level are resumed within 95 the producer will fail, by reason of the impossibility of rocking said arm to the right, past the plane of its vertical position.

The fuel feeding mechanism 7 is placed eccentrically to the gas producing chamber 100 4, and as the fuel bed is rotated by the action of the worm 5 and annular rack 6, the fuel falling by gravity into the chamber 4 will be brought beneath the radially disposed end of the member 19 and leveled to produce 105 a uniform surface. If the fuel accumulates beyond its desired limit, it will swing the member 19 on its axis 20 until the arm 27 is swung to the left of a vertical plane passing through the axis of the shaft 28, allowing the arm 27 to swing by gravity into the position shown in Fig. 2, thereby permanently disconnecting the fuel feeding mechanism from its operating power until the 110 arm 27 has been restored by the attendant 115 to its normal position, as shown in Fig. 1.

The feeding mechanism, therefore, becomes controlled by the height of the leveled surface of the fuel in the gas producing chamber, thereby preventing an excessive 120 thickness of the fuel bed which is kept uniform by the leveling action of the member 19 and the rotation of the fuel beneath it.

I claim:

1. In a gas producer, a rotating gas producing chamber, means for supplying fuel to said chamber by gravity, eccentrically to its axis of rotation, means for leveling the fuel during the rotation of said chamber, and means for checking the flow of fuel de- 125 130

terminated by the height of fuel in the fuel chamber.

3. In a gas producer, a gas producing chamber, mechanism for feeding fuel into the top of the gas producing chamber, a swinging member resting on the fuel in said chamber, gravity actuated means for checking the flow of fuel into said chamber, and means for bringing said gravity actuated means into operation by the movement of said swinging member.

4. In a gas producer, a rotating gas producing chamber, rotative means for feeding fuel to said chamber eccentrically to its axis of rotation, a swinging fuel leveler journaled outside said chamber, with its free end resting on the fuel in said chamber, means for rotating the fuel feeding mechanism, a weighted lever operatively connected with the fuel feeding mechanism, to disconnect it from its operative mechanism, and a connection between said weighted lever and said fuel leveler, whereby said weighted lever is made to operate by gravity to interrupt the action of said fuel feeding mechanism as determined by the upward swinging movement of said fuel leveler.

5. In a gas producer, a fuel feeding device, means for operating said device to feed fuel to a gas producing chamber, a swinging weighted lever operatively connected with said operating means, and means controlled

by the height of fuel in the gas producing chamber for swinging said weighted lever from its normal position into a position to 35 act by gravity to interrupt the action of the fuel feeding device.

6. In a gas producer, a gas producing chamber, means for feeding fuel into the top of said chamber, a shaft journaled outside 40 of said chamber, an arm carried by said shaft, with its free end resting on the fuel in said chamber, an arm carried by said shaft outside of said chamber, means for operating the fuel feeding mechanism, a weighted 45 lever, a slotted link connecting said weighted lever and said outside arm, and an offset arm on said weighted lever for disconnecting the operating mechanism from the fuel feeding device when said weighted lever is swung 50 by gravity.

6. In a gas producer, a fuel feeding device, constantly operating means for actuating said feeding device, gravity actuated means for detaching said operating means from the 55 feeding device, and means controlled by the rise in the fuel level in the producer for putting the gravity actuated means into operation.

Dated this twentieth day of January, 1915. 60
